DESIGN FOR A WINDOW DISPLAY BLOCK FIXTURE

Richard F. Harper, Benton Harbor, Mich., as-
signor to Paramount Sales, Inc., Benton Harbor,
Mich., a corporation

Application August 14, 1935, Serial No. 58,125

Term of patent 7 years

To all whom it may concern:

Be it known that I, Richard F. Harper, a citizen of the United States, residing at Benton Harbor, in the county of Berrien and State of Michigan, have invented a new, original, and ornamental Design for a Window Display Block Fixture, of which the following is a specification, reference being had to the accompanying drawing,

forming part thereof, in which Fig. 1 is a top plan view and Fig. 2 an elevational view of the article showing my new design.

I claim:—

The ornamental design for a window display block fixture, as shown.

In testimony whereof I affix my signature.

RICHARD F. HARPER.
